[57] CLAIM

The ornamental design for a lipstick garter, as shown and described.

DESCRIPTION

FIG. 1 is a perspective view of a lipstick garter showing my new design;

FIG. 2 is a top plan view with the bottom plan view being a mirror image thereof;

FIG. 3 is a right side elevational view with the left side being a mirror image thereof;

FIG. 4 is a rear elevational view thereof;

FIG. 5 is a front elevational view thereof; and,

FIG. 6 is an environmental perspective view thereof.

The broken line showing of the lipstick in FIGS. 3 and 6 and the ruffles and human form in FIG. 6 is for illustrative purposes only and forms no part of the claimed design. The drawing of FIGS. 1 through 6 is drawn broken away for purposes of illustration.
